UNITED STATES PATENT OFFICE.

RUDOLF E. HELLMUND, OF SWISSVALE, PENNSYLVANIA, ASSIGNOR TO WESTINGHOUSE ELECTRIC AND MANUFACTURING COMPANY, A CORPORATION OF PENNSYLVANIA.

PHASE-CONVERTER EXCITING SYSTEM.

1,376,429.

Specification of Letters Patent.

Patented May 3, 1921.

Application filed August 7, 1916. Serial No. 113,454.

To all whom it may concern:

Be it known that I, RUDOLF E. HELLMUND, a subject of the Emperor of Germany, and a resident of Swissvale, in the county of Allegheny and State of Pennsylvania, have invented a new and useful Improvement in Phase-Converter Exciting Systems, of which the following is a specification.

My invention relates to regulating apparatus for phase-converter of the rotary type, and it has for its object to provide means whereby the different component voltages, in apparatus of the character designated, may be automatically regulated with respect to each other, throughout wide variations in load.

In the accompanying drawings, Figure 1 is a diagrammatic view of a phase-converter of the T-connected, rotary type, together with auxiliary automatic compounding and phase-correcting apparatus; Figs. 2 to 6, inclusive, and Figs. 8 to 13, inclusive, are diagrammatic views of modifications of the system shown in Fig. 1; and Fig. 7 is a sequence chart setting forth the order of switch manipulation in the system of Fig. 6 for the operation thereof in accordance with my invention.

In the operation of phase-converter, such, for example, as those employed for deriving three-phase currents from a single-phase source or for balancing unbalanced polyphase systems, it is a well known fact that, with an increase of load, there is a tendency for the secondary induced voltage to fall off because of the drops in the stator and rotor circuits. This is an undesirable condition as it promotes unbalancing in the polyphase distributing system, with resultant unsatisfactory operation of polyphase apparatus connected thereto. In my copending application, Serial No. 108,567, filed July 11, 1916, I set forth means whereby an extraneous voltage is introduced into the rotor circuits for forcing the load current therethrough as by a suitable synchronous booster. By suitable adjustment of said auxiliary voltage, the drop across the rotary terminals may be suitably compensated for and I may, in fact, by a further increase in said auxiliary voltage, compensate for the voltage drops in the primary winding itself and in associated apparatus.

It has been found that the load currents in the rotor circuits of a phase-converter are

of twice the frequency of the supply circuit and it is therefore necessary that the above-mentioned, auxiliary, compensating voltage be of double frequency in order to properly perform its function.

In the present invention, I provide means whereby direct-current, exciting apparatus is combined with said compounding exciting means so that automatic control of the power-factor of the phase-converter and of associated apparatus may be obtained.

Referring to Fig. 1 of the drawing for a more detailed understanding of my invention, I show a phase-converter of the rotary type at 14, said phase converter comprising a primary stator winding 15, a secondary stator winding 16 and a rotor 17 provided with a three-phase winding 18. The windings 15 and 16 are joined to form the ordinary T-connection, as is well known in the art. The outer terminals of the rotor winding 18 are connected, through suitable slip rings 19 and through the field windings 20-20 of a polyphase commutator machine 21, to the brushes of said machine. The rotor of the machine 21 is mounted on the shaft of the phase-converter 14 or otherwise mechanically coupled thereto so as to be driven thereby. The field windings 20-20 are circumferentially displaced, with respect to their associated brushes, so that they combine the effects of exciting and inducing windings. There is generated in the rotor of the machine 21, therefore, double-frequency currents of such amount and phase as to properly compound the machine 14, compensating not only for ohmic but also for reactive drops therein, all as explained in detail in my afore-mentioned application.

An additional machine 22 of the commutator type is also mounted upon the shaft of the phase converter 17 and comprises an armature 23, an exciting field winding 24 and a short-circuited neutralizing or compensating field winding 25. The exciting winding 24 may be energized from any suitable direct-current source, such, for example, as a battery 26, through an adjustable resistor 27. The armature of the machine 22 is connected in circuit between one of the phases of the winding 18 and the machine 21.

With the connections as described, direct current is produced in the machine 22 and flows through the appropriate phases of the winding 18, causing the rotor 17 of the phase

converter 14 to lock into synchronism and to thereafter run synchronously. By suitable adjustment of the resistor 27, the corresponding unidirectional field in the rotor 17 5 may be adjusted in strength, with corresponding adjustment of the power factor of the phase converter 14, as is well known in connection with the ordinary synchronous condenser.

10 An important function of the neutralizing winding 25 in the operation of the machine 22 is the elimination of the alternating cross-field which is set up therein by the flow of a portion of the load current of the 15 rotor 17 therethrough.

It is unnecessary to employ two distinct machines on the shaft of the phase-converter, as the functions of a direct-current exciter and of an alternating-current ex- 20 citer may be combined in a single machine.

A system of this character is shown in Fig. 2 wherein, so far as possible, like parts to those employed in the system of Fig. 1 are denoted by like reference numerals. The 25 composite exciting machine is shown at 28 and includes a rotor 29 of such length that its windings may be under the influence of two stators, one of which carries the alternating-current field windings 20—20 and the 30 other of which carries the unidirectional current field windings 24 and 25. The machine 29 is shown as driven by a direct-current motor 30, rather than being attached to the shaft of the phase-converter, but, ob- 35 viously, either of these methods of driving may be employed, as is found most convenient.

The machine 28 is shown greatly exaggerated in dimensions, with respect to the 40 phase-converter 14, for the sake of clearness but it will be understood that, in practice, said two machines bear substantially the same ratio to each other in size that is borne by the ordinary generator and its exciter.

45 I may go still further in simplifying the exciting means for a phase-converter by placing all the field windings therefor on a single stator, as indicated in Fig. 3. The composite exciter machine is shown at 31 50 and need be provided with but a single pair of brushes, as it is necessary to bring out but one phase from the polyphase rotor winding 18 of the phase-converter 14. The double-frequency alternating excitation of 55 the machine 31 is provided by a single set of field windings 20, and a unidirectional current component of the excitation is provided by a field winding 24, as before. The field windings 20 and 24 should be mounted 60 on separate polar projections, and each polar projection carrying a portion of the unidirectional current winding 24 should be provided with a short-circuited field winding 25 in order to prevent alternating flux from 65 threading the coil 24.

Another system embodying a composite exciter is shown in Fig. 4. The composite exciter 31 is of the polyphase commutator type and is provided with three exciting field windings 20—20, operating as in Fig. 1. 70 A fourth field winding 32 is mounted substantially in line with one of the field windings 20 and is excited by direct-current from a generator 33 driven by a repulsion motor 34. The circuit joining the generator 33 75 and the field winding 32 includes the secondary winding 35 of a transformer 36, the primary winding 37 of which is in series with the field winding 20 that is coaxial with the field winding 32. With these connec- 80 tions, the alternating current of the winding 20 induces an alternating electromotive force in the field winding 32 but the secondary winding 35 is so connected that the electromotive force of the transformer 36 is equal 85 thereto and opposite in its effects. By this means, the harmful effect of the alternating flux threading the field winding 32 in inducing an alternating-current voltage in the unidirectional exciting circuit and producing 90 resultant disturbance by superimposing alternating waves upon the unidirectional exciting current is removed.

The exciter machine 31 is driven by a commutator motor 38, said motor comprising a 95 short-circuited armature 39, an exciting field winding 40 and an inducing field winding 41. The exciting field winding 40 is connected across the supply transformer, and the field 100 41 is energized, in accordance with the load current of the phase-converter 14, through a suitable current transformer 42. Thus, the speed of the motor 38 varies with the load, which provides additional means for increasing both the direct-current and the 105 alternating-current excitation with the converter load, with resultant possibility of increased compensating and compounding effects. The motor 34, driving the generator 110 33, is energized in accordance with the voltage of the secondary winding 16 of the phase-converter 14.

A still further consolidation and simplification of my system may be effected, as shown in Fig. 5, by combining the windings 115 20 and 32 of Fig. 4 into a single winding 43 traversed by both the alternating and the unidirectional exciting currents. The transformer 36 operates as in the system of Fig. 4, eliminating the effect of the alternating 120 flux upon the unidirectional exciting current.

A certain compounding effect may be obtained, in a system of the character described, by placing the neutralizing field 125 winding in series with the armature, designing it for slight over-compensation and then by shifting the armature brushes slightly away from the axis thereof. A system of this character is shown in Fig. 130

6 wherein an exciting machine 31 is provided with a single pair of brushes for connection in a single phase of the rotor winding of the phase-converter 14, and further 5 comprises an exciting winding 44, a neutralizing winding 45 and an additional field winding 46 in alignment with the winding 44.

The various elements of the system may 10 be interconnected by suitable switches 47 to 54, inclusive. The winding 44 is connected to be energized from a direct-current source 26 which, in addition, supplies a driving motor 30 for the exciting apparatus. For 15 starting, the switches 49 and 51 are closed, as indicated in Fig. 7, whereby the armature of the machine 31, the exciting field winding 46 and the neutralizing field winding 45 are all connected to the source in 20 series with the primary winding of the phase-converter. After the phase-converter has been started and brought up to substantially synchronous speed, the armature of the exciter 31 and the neutralizing 25 field winding 45 are connected in series with the rotor winding of the phase-converter by closing switches 47, 48, 50, 52 and 53 and opening the switches 49 and 51, all as indicated in the chart of Fig. 7. Under 30 these conditions, the field winding 44 supplies unidirectional excitation, and the field winding 46 is short circuited by the closure of the switch 53 to act as a damping winding and restrain alternating flux from 35 traversing the winding 44. The field winding 45 serves as a compensating winding and, in addition, supplies a small alternating-current field by reason of the brush displacement, said field inducing the desired 40 alternating electromotive force for compounding.

In the system of Fig. 8, the exciter machine 31 is provided with a unidirectional-current exciting winding 44, with an alternating-current exciting winding 46' in alignment therewith and with a short-circuited neutralizing winding 54 in line with the brushes. The winding 44 is energized from the source 26, and a transformer 36 45 interlinks the supply circuit thereof with the circuit of the phase-converter for the neutralization of the alternating electromotive force induced therein. At the outset, the switches 58 and 59 are closed and, for 50 subsequent operation, said switches are opened and the remaining switches closed. Thus, the winding 44 supplies a unidirectional field during normal operation and the winding 46' furnishes an alternating 55 field both during starting and subsequent operation.

In my aforementioned application, a system is disclosed in which the armature of the exciting machine is short circuited 60 through the brushes and the load currents

of the phase-converter traverse only the field windings of the exciter machine. In this manner, commutation troubles are avoided. Fig. 9 shows a system of this character wherein means are provided, in 70 addition, for supplying a unidirectional exciting current. The exciter machine 31 is shown as of the polyphase commutator type, the field windings 20-20 thereof being connected in star to the rotor winding 18 of the phase-converter 14 and the commutator including three, equally-spaced brushes 61 which are connected together. A unidirectional-current source 62 is inserted in one of the main leads to the rotor 75 17, as in the system of Fig. 1. The exciter machine 31 is shown arranged to be driven from the car axle 63, if the system in question is to be applied to a railway vehicle, thus illustrating another variation of my 80 85 invention.

As pointed out in my aforementioned application, it may, in certain instances, be undesirable to have the exciter machine derive its exciting current from the phase-converter because of the harmful effect on the phase-converter power-factor. It was accordingly proposed to render the exciter machine self-exciting, particular attention being directed to the desirable characteristics 90 of the Winter-Eichberg generator when used in this connection. A system of this character is shown in Fig. 10 wherein the exciter machine 31 is provided with a unidirectional-current field winding 24 and with a 95 short-circuited neutralizing or compensating winding 25 in line therewith. The armature of the machine 31 is provided with two sets of brushes 64-64 and 65-65 having a quadrature relation to each other. The 100 brushes 64-64, in quadrature to the exciting field winding 24, are connected in a phase of the rotor winding 18 of the phase converter 14. The brushes 65-65, in line with the exciting field winding 24, are connected together through the primary winding 35 of a transformer 36, the secondary winding of which is inserted in series with the brushes 64-64. By this arrangement, both alternating and direct-current excitation 105 are derived from the machine 31, as will appear from the following consideration. Double-frequency rotor current from the machine 14 flows through the brushes 64-64 and establishes an alternating-field 110 115 having a horizontal axis through the armature of the machine 31. Said alternating field produces a rotational, alternating electromotive force between the brushes 65-65, and said electromotive force is introduced 120 into the converter rotor circuit by the transformer 36. The field winding 24, which is excited by direct current from the battery 26, produces a vertical field through the armature of the machine 31, which, in turn, 125 130

produces a rotational unidirectional electromotive force between the brushes 64—64 to produce a flow of direct exciting current through the winding 18. The alternating field established in line with the brushes 65—65 by the flow of alternating current therethrough may be damped out either by a superimposed electromotive force in the direct-current exciting circuit or by the inducing winding 25. The rotor current of the converter now has a direct-current component which establishes a unidirectional field in line with the brushes 64—64, inducing, in turn, a rotational unidirectional voltage between the brushes 65—65. By proper design, said electromotive force may be used to assist the field winding 24 in producing the total unidirectional excitation of the machine 31.

20 The system of Fig. 11 is, in general, similar to that of Fig. 10 but the exciter machine 31 is rendered self-exciting, with respect to its unidirectional component, by connecting the field winding 24 between the brushes 64—64 through a regulating resistor 27. The exciting system may be started by first causing the machine 31 to pick up as a self-excited direct-current shunt machine as, for example, by opening a switch 66. Said switch is then closed, connecting the exciter through the rotor circuit of the converter, whereupon it supplies both alternating and direct current thereto. The field winding 24 has such a high resistance, as it is a shunt winding, that substantially no alternating flux threads therethrough. The armature of the machine 31, however, carries both alternating and direct current between the brushes 64—64, and, therefore, has both types of fields along the horizontal axes. Both alternating and direct rotational electromotive forces are therefore induced between the brushes 65—65. The alternating component is transferred into the rotor circuit through the transformer 36, whereas the unidirectional component serves merely to strengthen the unidirectional field in the vertical axis.

25 The system of Fig. 12 is the same as Fig. 11 except that a neutralizing winding 25 has been added to the machine 31, said winding being closed upon itself through an adjustable resistor 67. By this means, the alternating excitation may be adjusted, both in magnitude and in phase, thus rendering it possible to provide an alternating component of the exciting current that shall be out of phase with the rotor current of the converter.

30 It may, in some cases, be undesirable to use an exciter machine of the commutator type and, under these conditions, I may employ an alternating-current generator for the production of the desired double-frequency exciting current, as indicated in Fig.

35 13. The phase converter 14 carries, upon its shaft, the rotor 68 of an alternating-current generator 69 having twice as many poles as the phase-converter 14. The rotor field winding 18 of the rotor 14 is connected 70 through the armature coils 70—70 of the machine 69, said coils being arranged in star. The rotor 68 carries the usual direct-current, field windings 71—71 of an alternating-current generator of the rotating field type, 75 said field windings being energized from a source 72 through suitable slip rings 73. The source 72 constitutes a shunt-excited direct-current generator driven by a commutator motor 74, the armature of which is 80 connected across the secondary winding 16 of the machine 14. The motor 74 further comprises an exciting field winding 75 which is energized in accordance with the load current by a suitable current transformer 85 76. The connections are such that an increase in load produces a decrease in the component of the field electromotive force which is in line with the armature electromotive force, thus causing an increase in 90 the speed of the motor 75 with an increase in the load. The motor 75 may further be provided with a short-circuited inducing winding 77. A direct-current component for phase correction may be inserted in the 95 connection to one phase of the rotor circuit 18, as indicated at 78.

With the system arranged as above described, the fact that the exciter machine 69 has twice as many poles as the phase-converter 14 produces a double-frequency exciting current, as is desirable for compounding. By virtue of the supply connections shown, the speed of said exciting machine varies with the load, thus still further enhancing the compounding effect.

In all of the herein-described systems, it will be recognized that the direct and alternating exciting currents combine, as actually supplied to the phase-converter, to form a 110 single exciting current of pulsating or unsymmetrical alternating form.

While I have shown my invention in a plurality of forms, it will be obvious to those skilled in the art that it is susceptible 115 of various minor changes and modifications without departing from the spirit thereof and I desire, therefore, that only such limitations shall be placed thereupon as are imposed by the prior art or as are set forth in 120 the appended claims.

I claim as my invention:

1. The combination with a phase-converter of the rotary type, of coöoperating means for conductively supplying both direct and 125 alternating currents to a secondary winding thereof.

2. The combination with a source of alternating current, of a phase-converter of the rotary type, and coöoperating means for con- 130

ductively supplying both direct current and alternating current of twice the frequency of said source to a secondary winding of said converter.

5 3. The combination with a phase-converter of the rotary type provided with a wound secondary member, of a source of pulsating current, and connections from said source to a winding of said secondary member.

10 4. The combination with a phase-converter of the rotary type provided with a wound secondary member, of an auxiliary dynamo-electric machine, driving means therefor, connections from the terminals thereof to a secondary winding of said converter, and means for simultaneously producing unidirectional and alternating exciting fields in said auxiliary machine.

15 20 5. The combination with a source of alternating current, of a phase-converter provided with a wound secondary member con-

nected thereto, and means for supplying pulsating current to a winding of said secondary member, the frequency of pulsations thereof being substantially twice the frequency of said source.

6. The combination with a source of alternating current, of a phase-converter of the rotary type connected thereto, an auxiliary 30 dynamo-electric machine, driving means therefor, connections from the terminals of said auxiliary machine to a secondary winding of said converter, means for producing a unidirectional exciting flux in said auxiliary machine, and means for simultaneously producing an alternating exciting flux in said auxiliary machine of substantially twice the frequency of said source of alternating current.

In testimony whereof, I have hereunto subscribed my name this 21st day of July, 1916.

RUDOLF E. HELLMUND.
